UNITED STATES PATENT OFFICE.

OTTO ZEH, OF EISFELD, GERMANY.

PROCESS OF COLORING DOLL-HEADS.

SPECIFICATION forming part of Letters Patent No. 603,216, dated April 26, 1898.

Application filed September 30, 1896. Serial No. 607,479. (No specimens.)

To all whom it may concern:

Be it known that I, OTTO ZEH, of Eisfeld, in the German Empire, have invented new and useful Improvements in Processes of Coloring Doll-Heads, of which the following is a specification.

By means of this process it is possible to impart the effect of burnt-in color or stain to ordinary burnt white porcelain without using to this end any of the known methods for burning in the color. This is effected by applying certain colors to the porcelain and then coating the colored porcelain with a transparent lac. The color used to this end is a water-color, to which is added a little glue and glycerin. The porcelain is then stained with the color in question. This is best done by dipping the former into the latter, which produces a very thin coat of color upon the porcelain, so essential for the method in question, as opposed to the methods usually employed for painting of similar materials. After the porcelain has received this treatment it should again be dipped into highly-durable ground lac, which soaks into the coat of color, owing to the extreme weakness of the latter, and combines with it permanently on the surface of the porcelain.

The mixture of glue and glycerin is used to create the effect mentioned, the glue creating a very thin and even coat of color, permitting at the same time of the lac soaking through, while the glycerin prevents the coat of color becoming brittle and being knocked off.

After the ground lac has been thoroughly dried upon the coat of paint the material is treated once more with a thin coat of non-soluble dull lac, which can also be substituted by wax. When dry, the porcelain has the ap-

pearance of having been treated with burnt colors—*i.e.*, as if it had been painted—while the coating possesses the great advantage that it throws up the coloring in extraordinary purity and is not effected by moisture, as it cannot be dissolved, owing to the presence of the lac.

The porcelain used for the above-described process shall not be porous, and held to the tongue it should not suck. It may be unglazed or glazed. The unglazed porcelain should be burned to such a manner that it cannot be slit by means of a knife. In no wise a sinking of color or lac into the porcelain takes place.

Having now described my invention, what I claim, and desire to secure by Letters Patent, is—

The method of creating the effect of burnt colors upon burnt white porcelain which consists in first applying to the said porcelain a thin coating of a water-color containing glue and glycerin; second, in applying to this coating of water-color a thin coating of transparent lac which sinks into and becomes a part of the said initial coating; third in allowing the before-mentioned coating to dry and subsequently applying to the same a thin coating of dull lac for the purpose of producing a dull instead of a glossy effect, substantially as described.

In testimony that I claim the foregoing as my invention I have signed my name in presence of two subscribing witnesses.

OTTO ZEH.

Witnesses:

ADOLPH ZEH,
ALVIN FLORSCHUTZ.
